UNITED STATES PATENT OFFICE.

FRANK RUDOLPHI, OF CHICAGO, ILLINOIS, ASSIGNOR TO AMERICAN CAN COMPANY, OF NEW YORK, N. Y., A CORPORATION OF NEW JERSEY.

DESIGN FOR A SHEET-METAL DISPLAY-CAN.

No. 38,170.

Specification for Design.

Patented Aug. 14, 1906.

Application filed May 28, 1906. Serial No. 319,214. Term of patent 14 years.

To all whom it may concern:

Be it known that I, FRANK RUDOLPHI, a citizen of the United States, residing at Chicago, in the county of Cook and State of Illinois, have invented a new, original, and ornamental Design for a Sheet-Metal Display-Can, of which the following is a specification, reference being had to the accompanying drawing, forming part thereof.

The figure is a front elevation of a sheet-metal display-can, showing my new design.

I claim—

The ornamental design for a sheet-metal display-can, as shown.

FRANK RUDOLPHI.
